VASE HOLDER

Filed Nov. 27, 1925

Inventor:

Charles S. Baron,
By Atkins & Atkins,

Attorneys.

UNITED STATES PATENT OFFICE.

CHARLES S. BARON, OF TIFFIN, OHIO.

VASE HOLDER.

Application filed November 27, 1925. Serial No. 71,832.

My invention relates to mechanism for securely mounting upon a vertical wall, as of an automobile, a vase, for holding flowers, for example.

5 The object of my invention is to produce a vase holder of the kind just referred to, that is distinctively simple, strong, durable, and economical to manufacture.

What constitutes my invention will be 10 hereinafter specified in detail, and succinctly defined in the appended claims.

In the accompanying drawings,

Figure I is a side elevation of a preferred form of my vase holder complete.

15 Figure II is a horizontal section on line II—II of Figure I.

Figure III is a plan view of a blank made of a single sheet of metal.

Figure IV is a detail view of one means 20 for preventing rotation of the vase while it is held in the metallic member of the holder.

Figure V is a similar view of a modification of the subject matter of Figure IV.

Figure VI is a similar view of a still further modification of the same.

Figure VII is a side elevation of a part of the device shown in Figure VI.

Figure VIII is a view corresponding to Figure VII showing zone defining beads as 30 a modification of Figure I.

Referring to the numerals on the drawing, 1 indicates a vase which may be, in general, of any preferred dimensions, shape, and design. Its distinguishing feature is a 35 clip-confining zone 2, which may be defined by shoulders 3 and 4 made as by moulding for example, so as to form in the body of the vase a depression in the glass of which the vase is preferably, though not necessarily, made. The zone, if preferred, may be otherwise defined, in effect, as by beads 5 and 6, 40 shown in Figure VIII, raised above the general contour surface of the vase.

The shouder 4 or bead 6, whichever be employed, is preferably made of smaller diameter than its companion member 3 or 5, in order to facilitate the application to the zone of the clip hereinafter specified, the members 3 or 5 being those which, in use, sustain the weight of the vase, however light it be, upon the clip.

The holder proper consists of a two-footed base 8 having secured to it a bifurcated clip 9 made of resilient metal.

55 The said base and clip may be made, if desired, of separate pieces secured together by

any suitable means to form a unitary structure, but I prefer, especially, for considerations of simplicity and economy of manufacture, to combine them integrally by making them from a blank 10 consisting of a single piece of suitable flat metal, as shown by way of example, in Figure III.

The blank 10 is made preferably in the shape of a cross, having two opposite long 60 arms 11, and, at right angles to them, arms 12 whose respective lengths are preferably about half that of the arms 11.

To convert the blank 10 into a holding member, the free ends of the arms 11 are 65 shaped as by bending to form the clip 9 to fit snugly the zone 2 which they are intended to encircle, their ends being juxtaposed when bent so as preferably to present between them an open space 15.

75 The arms 12 are in like manner made to constitute the two feet of the base 8 for the support of the clips upon a wall, and are to that end provided, respectively, with screw holes 16, for the reception of ordinary 80 screws, not necessary to illustrate. The edges of the arms 12 are also preferably shaped, as by crimping, to give them an in-turned outside stiffening flange 17, in the completed article.

85 The clip 9 may be applied to a zone 2 having a smooth cylindrical contour. In such case the vase may rotate in the clip, without danger of separation of one part from the other. If desired, however, rotation of the vase in the clip may be provided against, in any one of several different ways. For example, the free end of one or both of the arms 11 may be provided with an aperture 18 into each of which a lug 19 90 projecting in alignment with it from the surface of the zone 2 may, as shown in Figure IV, enter with latching effect. Instead of lug 19 and aperture 18, one of the arms 11 (or both of them) may be provided with an inturned flange 20 adapted, with like effect, to take into a transverse groove 21 in the zone 2, as shown in Figure V.

95 If the body of the base be of angular shape in cross section, such as that shown for example in Figure VI, the zone 2 may be, of course, of cylindrical shape, as already specified, or it may also be like the body of the vase, for instance, of angular transverse contour. In the case last mentioned, the zone 105 indicated in Figure VI by the numeral 22, may be shaped to fit a correspondingly shaped

clip 23. The corresponding angularity of the contours of the zone 22 and of the clip 23, respectively, will serve, without other provision, to hold the vase irrevolubly in the 5 clip.

The operation of my device will, it is believed, be clearly understood from the foregoing specification without further description.

10 What I claim is:

1. In combination with a vase, a supporting clip having substantially horizontally disposed resilient arms engaging the vase, a pair of oppositely disposed feet extending vertically from said clip for detachably securing the same to a supporting member, said vase having spaced means

formed thereon and coacting with said arm for normally preventing removal of the vase from the clip.

2. In combination with a vase having an angularly formed external portion, a supporting clip having substantially horizontally disposed resilient arms engaging said external portion, a pair of oppositely disposed feet extending vertically from said clip for detachably securing the same to a supporting member, said vase having spaced means formed thereon and coacting with said arms for normally preventing removal 30 of the vase from the clip.

In testimony whereof, I have hereunto set my hand.

CHARLES S. BARON.
